CLAIM

The ornamental design for a dual color camera with
microscope and digital analyzer work station, as shown
and described.

DESCRIPTION

FIG. 1 is a perspective view of a dual color camera with
microscope and digital analyzer work station showing
my new design;

FIG. 2 is a rear, right side perspective view thereof;

FIG. 3 is a rear, left side perspective view thereof.

FIG.1

FIG.2

FIG.3

UNITED STATES PATENT AND TRADEMARK OFFICE
CERTIFICATE OF CORRECTION

PATENT NO. : Des. 322,857
DATED : December 31, 1991
INVENTOR(S) : James W. Bacus

It is certified that error appears in the above-identified patent and that said Letters Patent is hereby corrected as shown below:

On the Title page, insert -- item [62] under Related U.S. Application Data
This application is a continuation-in-part of patent application Serial No. 927,285, filed November 4, 1986, now Patent No. 5,018,209, which in turn is a continuation-in-part of application Serial No. 794,937 filed November 4, 1985, now Patent No. 4,741,043.

Signed and Sealed this
Twenty-fifth Day of May, 1993

Attest:

MICHAEL K. KIRK

Attesting Officer

Acting Commissioner of Patents and Trademarks
